ABSTRACT OF THE DISCLOSURE

This invention is the integral formation in an envelope of a tear strip by means of which the envelope may be readily opened. The term "envelope" not only includes envelopes for letters and other papers, but also bags, generally small bags, sachets, etc. which are made of tearable material and which are generally sealable or sealed to hold their contents until they are to be opened. The tear strip is integrally formed by embossing one or more rows of small bars, or elongated pimples, somewhat adjacent one elongate edge of the envelope, and preferably stopping the row short of one or both ends of the envelope. The bars may be embossed from either or both faces of the envelope, and, when from both faces, the embossed bars will alternate, and preferably be contiguous. In another form, two rows of embossed bars may have their confronting ends offset and interengaging. In other forms, two parallel rows, slightly spaced apart are provided, and in another form, a row of perforations is provided parallel to and between the two rows. The embossed bars may extend at right angles to the row, or may extend parallel to each other but at an acute angle to the row or rows. In the single row form, the tear line develops between the ends of the bars. In the two row forms, the tear line develops between the two rows, and if a row of perforations is present therebetween, then the tear line develops along the row of perforations. Further, the row of embossed bars serves to hold the front and back sides of the envelope locked together so that the contents, such as a letter or pieces of paper, cannot extend between the front and back of the envelope, and thus cannot be accidentally torn when the envelope is opened.

This invention relates to a readily openable envelope having an integrally formed tear strip, on which an application for patent has already been filed in France on Sept. 9, 1966, Ser. No. 75,843, and first addition thereto on July 20, 1967, Ser. No. 114,987, and priority under the International Convention is claimed herein.

Objects of this invention

It is an object of this invention to provide a readily openable envelope in which the opening means is integrally provided in the envelope by dry printing or embossing a row of bars, from one or both faces thereof, such row being located adjacent one longitudinal edge of the envelope.

A further object of this invention is to provide a weakened opening tear strip integrally formed in the envelope, adjacent one elongate edge, which will also maintain the envelope contents safe from being liable to be torn in the act of tearing the opening tear strip.

A further object is to provide an improvement over applicant's previous U.S. Patent No. 2,954,916 of Oct. 4, 1960.

A further object of this invention is to provide a readily openable envelope wherein, in the case of a very thin paper envelope, such as an airmail envelope, the en-

velope may be reinforced at the tear line provided by this invention by inserting a strip or band of material into the tear strip area, between the front and back faces of the envelope, which band is maintained in place by the row 5 of embossed bars being provided therethrough simultaneously with the embossed bars through the front and back faces of the envelope.

A further object of this invention is to provide a weakened tear line integrally in the envelope which is provided by one or more row of embosses closely adjacent each other, which row or rows of embosses may be impressed from either of both faces of the envelope.

A further object of this invention is to provide an integrally formed tear strip or tear line in an envelope, 10 which envelope may be a bag or container or may be a bag or container for other materials than letter paper.

Description of figures

With the above and related objects in view, this invention consists in the details of construction and combination of parts, as will be more fully understood from the following description, when read in conjunction with the accompanying drawing, in which:

FIG. 1 is a view of the back side of a stationery envelope of a small standard size to which this invention has been applied.

FIG. 2 is a view of a legal size envelope, partly broken away, showing the same form of invention.

FIG. 3 shows an unfolded airmail envelope with a reinforcement band included therein.

FIG. 4 is a sectional view on line 4—4 of FIG. 3.

FIG. 5 is a back view of an envelope with a different form of this invention.

FIG. 6 is a front fragmentary view of the tear strip of the envelope of FIG. 5, in the process of being opened.

FIG. 7 is an enlarged fragmentary view showing the details of the form of invention in FIGS. 5 and 6.

FIGS. 8, 9, 10 and 11 are similar enlarged detail fragments of different modified forms of tear strips.

FIG. 12 is a plan view of an envelope in the form of a bag or sachet to which the invention has been applied.

FIG. 13 is a section on line 13—13 of FIG. 12.

Description of invention

There is shown at 1 in FIG. 1, a standard small size envelope having the usual sealing flag 2 extending over its back face, to which this invention in the form of a row 3 of bars 6 and 7 have been embossed alternately from both the front and back faces of the envelope.

In FIG. 2, a standard legal size envelope 11 is shown, with a row 13 of alternate, oppositely embossed bars 16 and 17, stopping short of the adjacent end of the envelope at 14 and 15. It will be noted that the bars 6 or 16, embossed on the front face, alternate with and are contiguous with the bars 7 or 17 embossed on the rear face of the envelope 1. In enlarged detail, as shown in FIGS. 8 through 11 they are generally rounded at both ends, although they may be straight at one end, as shown in FIG. 7, or both ends as shown in FIGS. 1 to 4. The row 3 or 13 stops short of each end of the envelope, as shown at 4 and 5, or 14 and 15.

Operation of invention

In FIGS. 1 and 2, the ends of the bars 6 and 7 or 16 and 17 tend to be stronger than the intermediate portion, and thus, when a tear is started by holding the envelopes with the end areas 4 and 5, or 14 and 15, between the fingers of one hand, the tear line will develop between the ends of the bars along their middle or intermediate areas and the envelope will be torn open. The presence 65 of the embosses 6 and 7 or 16 and 17 prevent the enclosed paper or letter in the envelope from entering the

tear strip area of the envelope, and thus cannot be torn when opening the envelope along the tear strip row 3 or 13.

Further detailed description

In FIGS. 3 and 4, a very thin paper airmail envelope 20 is shown having a front panel 21 connected with the rear panel 27 at the fold line 28, with a band or strip of material 26, preferably of paper or material the same as that of the envelope, the band 26 extending between the front panel 21 and rear panel 27 of the airmail envelope 20 as far as the inside of the fold line 28, the band 26 being only slightly wider than the width of the embossed bars of the row 23. The tearing operation of this form is the same as described above—the tearing line will develop along the intermediate portion of the bars of the row 23.

Other forms of invention

In FIGS. 5, 6 and 7 is shown a "zipper" form of this invention. In this form the envelope 31 has two parallel offset or staggered rows 33 and 34 of embossed bars extending up through the front face of the envelope. The offset confronting ends 35, which are rounded, it will be noted, interengage each other and provide a line of weakened resistance along which the tearing line 36 will develop when the edge area 32 is torn away. In this case, the bars are embossed on the front face by being impressed through the rear face of the envelope 31 to project above the front face but obviously may be embossed through the front face to project on the rear face. However, in this "zipper" the interengaged ends of the embossed bars provide the line of weakness or tearing line 36, as shown in FIG. 6.

In the form shown in FIG. 8, two parallel rows of bars 43 and 44 are embossed from one envelope face only, and thus provide a tear line 45 between them. It will be noted that the bars 43 and 44 are here shown as extending at right angles to the direction of the row, and although not offset, could well be offset. It is also noted that the embossed bars are spaced apart a distance not greater than their width.

The form shown in FIG. 9 is similar to that in FIG. 8, plus a tearing line provided by a row of spaced perforations 55 parallel to and between the two rows of embossed bars 53 and 54.

The form in FIG. 10 differs from that of FIG. 9 by having the individual embossed bars 63 and 64 extend at an acute angle to the direction of the rows, the tearing line being provided by the row of perforations 65.

The form in FIG. 11 has its embossed bars 73 and 74 at acute angles to each other and to the direction of the rows, and in addition, there is a row of linearly extending embossed bars 75 alternating with perforations 76 providing the tearing line between the rows of angularly extending embossed bars 73 and 74.

In FIGS. 12 and 13, the envelope 81 is a sachet or bag, which may be larger than the conventional envelope sizes, and may be used for contents other than papers or letters, such as beauty powder, confectionery, or other articles. The embossed bars 83 and 84 making up the row 85 may be the same as shown in any of the preceding forms of the invention.

Any form of the invention may be provided by means of an embossing tool or printing tool, from one or both faces, and if desired, ink may be added. However, the embossing or printing act, whether dry or with ink, also serves, in a sense, to compress or "solder" the two faces or sheets of the envelope together along the embossed rows, so that a letter placed in the envelope will not enter therebetween, and thus will not be accidentally torn when the envelope is opened along the tearing line provided. Any other suitable manner of manufacture may be used.

In the drawings, like numbers refer to like parts, and for the purposes of explication, marshalled below are the

numbered parts of the improved readily openable envelope having an integrally formed tear strip:

- 1—small envelope
- 2—flap
- 3—row of embossed bars
- 4—one end margin
- 5—other end margin
- 6—bars embossed from one face of the envelope
- 7—alternate contiguous bars embossed from the other face
- 10 11—legal size envelope
- 12—row of embossed bars, similar to 3
- 13—one end margin
- 14—other end margin
- 15 16—bars embossed from one face
- 17—bars embossed from the other face
- 18—airmail envelope of thin paper
- 19—front panel of 20
- 20—row of embossed bars
- 21—end margin
- 22—other end margin
- 23—reinforcement band or strip of material
- 24—rear panel of 20
- 25—fold line of 20
- 26—envelope of FIGS. 5, 6 and 7
- 27—edge area of 31
- 28—row of bars in 31
- 29—offset row of bars in 31
- 30 31—offset confronting ends of 33 and 34
- 32—tearing line of 35
- 33—row in FIG. 8
- 34—other row in FIG. 8
- 35—tear line between 43 and 44
- 36—row in FIG. 9
- 37—other row in FIG. 9
- 38—tearing line between 53 and 54
- 39—acute angle embosses in FIG. 10
- 40 41—other acute angle embosses in FIG. 10
- 42—tearing line of perforations between 63 and 64
- 43—acute angle embosses in FIG. 11
- 44—other acute angle embosses in FIG. 11
- 45—linearly extending embossed bars between 73 and 74
- 46—alternating perforations in 75
- 47—sachet or bag in FIGS. 12 and 13
- 48—embossed bars
- 49—embossed bars
- 50 51—row of 83 and 84.
- 52 Having thus set forth and disclosed the nature of this invention, what is claimed is:
- 53 1. A readily openable envelope comprising an envelope, said envelope having a tear strip integrally formed therein, said tear strip being slightly spaced from and extending along at least one elongate edge of said envelope
- 54 2. A readily openable envelope comprising a row of adjacent bars embossed on one face of said envelope from the opposite face thereof providing a readily tearable line, said row of bars being embossed alternately from opposite faces of said envelope, said alternate embossed bars being contiguous to each other.
- 55 3. A readily openable envelope comprising an envelope, said envelope having a tear strip integrally formed therein, said tear strip comprising a row of adjacent bars embossed on one face of said envelope from the opposite face thereof providing a readily tearable line, said tear strip also including a second row of similar embossed bars parallel to said first row.
- 56 4. A readily openable envelope comprising an envelope, said envelope having a tear strip integrally formed therein, said tear strip being slightly spaced from and extending along at least one elongate edge of said envelope, said tear strip comprising a row of adjacent bars embossed on one face of said envelope from the opposite

face thereof providing a readily tearable line, said row of bars being embossed alternately from opposite faces of said envelope, said tear strip also including a second row of similar embossed bars parallel to said first row, said embossed bars of one row being offset with relation to said embossed bars of said other row, the confronting ends of each of said row of embossed bars extending partly between the confronting ends of the other row of said embossed bars.

4. A readily openable envelope comprising an envelope, said envelope having a tear strip integrally formed therein, said tear strip being slightly spaced from and extending along at least one elongate edge of said envelope, said tear strip comprising a row of adjacent bars embossed on one face of said envelope from the opposite face thereof providing a readily tearable line, and a reinforcement band of material held in place between the front and back faces of said envelope by said bars also being embossed therethrough.

5. A readily openable envelope comprising an envelope, said envelope having a tear strip integrally formed therein, said tear strip being slightly spaced from and extending along at least one elongate edge of said envelope, said tear strip comprising a row of adjacent bars embossed on one face of said envelope from the opposite face thereof providing a readily tearable line, said row of bars being embossed alternately from opposite faces of said envelope, said tear strip also including a second row of similar embossed bars parallel to said first row, said two rows of embossed bars being slightly spaced

10

15

20

25

30

apart, and a row of perforations extending between said two rows of embossed bars.

6. A readily openable envelope comprising an envelope, said envelope having a tear strip integrally formed therein, said tear strip being slightly spaced from and extending along at least one elongate edge of said envelope, said tear strip comprising a row of adjacent bars embossed on one face of said envelope from the opposite face thereof providing a readily tearable line, said row of bars being embossed alternately from opposite faces of said envelope, said tear strip also including a second row of similar embossed bars parallel to said first row, said two rows of embossed bars being slightly spaced apart, the bars of each row being parallel to the other bars of the same row and the bars of each row being at an angle to the bars of the other row.
